[57] CLAIM

The ornamental design for a side mirror for an automotive vehicle, substantially as shown and described.

DESCRIPTION

FIG. 1 is a rear perspective view of a side mirror for an automotive vehicle showing my new design for mounting horizontally on the left side of a vehicle;

FIG. 2 is a left side elevational view thereof;

FIG. 3 is a top plan view thereof;

FIG. 4 is a bottom plan view thereof;

FIG. 5 is a front elevational view thereof;

FIG. 6 is a rear perspective view of a side mirror for an automotive vehicle showing a second embodiment of my new design the sole difference being that it is for mounting horizontally on the right side of a vehicle;

FIG. 7 is a rear perspective view of the mirror of FIG. 1 rotated to an alternate position for mounting vertically on the right side of a vehicle; and

FIG. 8 is a rear perspective view of the mirror of FIG. 6 rotated to an alternate position for mounting vertically on the left side of a vehicle.
